UNITED STATES PATENT OFFICE.

CHRISTIAN B. CHRISTIANS, JR., OF SAN ANTONIO, TEXAS.

ROAD-REPAIRING MACHINE.

Application filed February 24, 1926. Serial No. 90,357.

My invention relates generally to machines for use in road construction and maintenance work and has in view more particularly a device whereby irregularities and depressions in a road are automatically filled up and graded.

It is an object of my invention to provide means for carrying the repair materials essential and also to automatically control the distribution thereof upon the road surface.

It is also an object of my invention to provide means whereby the depth and size of the depression or irregularity in the road will control the amount of materials deposited in said depression or irregularity.

A further object of my invention is to provide means whereby the size or depth of the depression or irregularity in the road will govern the rate of flow of material into the depression or irregularity so that uniform motion of the vehicle along the road is possible.

With these and other objects in view as will hereinafter appear, my invention consists in the construction arrangement and combination of the various parts of my device, whereby the objects contemplated are attained. As hereinafter more fully set forth, pointed out in my claims, and illustrated in accompanying drawings, in which:

Figure 1 is a vertical cross sectional view of my invention.

Figure 2 is a plan view on the section lines 2—2 of Figure 1 looking in the directions of the arrows.

Figure 3 is a vertical cross sectional view on the lines 3—3 of Figure 2 looking in the direction of the arrows.

In the drawings similar reference characters refer to like parts in the various Figures.

Referring to the drawings 10 and 11 indicate two skids having cross bars 12 and 13 for bracing the same. Upon each skid are two supports 14 and 15 each of which is composed of a series of blocks superposed upon one another having the front ends thereof, terminating in staggered relation, so that the elevation of my device, with relation to the skids and the road may be varied at will.

Extending between the supports 14 is a supporting member 16 and extending between the supports 15 is a supporting member 17 upon which my entire device rests. The ends of the supporting members 16 and

17 terminate in downwardly disposed U-shaped ends 18 which are adapted to rest upon the staggered portions of the supports 14 and 15.

Resting upon the members 16 and 17 and secured thereto in any desired manner are the horizontally disposed members 19 and 20, which are placed close to the ends 18 of the supporting members 16 and 17. Rising from the member 19 are the standards 21 and 22 and from the member 20 the standards 23 and 24. The standards 21 and 22 are joined at their tops by the member 25 and the standard 23 and 24 are joined by the member 26. Extending between the horizontally disposed members 25 and 26 are the bracing bars 27, 28, 29 and 30, while the members 19 and 20 are braced by the bars 31, 32 and 33. Instead of the above described form of supports and bracing, any other suitable type of construction may be used.

Secured to the brace bar 32 and extending forwardly therefrom are two brackets 34 and 35 in which is pivoted a trigger arm 36 carrying at the lower end thereof a roller 37 which is adapted to roll along the surface of the road and into any depression in the road. To the other end of the trigger bar a metal loop 39 is pivoted in any suitable manner and through this loop passes a cable or rope 38 which then leads over two pulleys 40 secured upon the horizontally disposed bar 41. From the pulleys 40, both ends of the cable 38 extend over the pulleys 42, which are also attached to the bar 41. The ends of the cable 38 are fastened to two weights 43, whose function is to keep the roller 37 in constant contact with the road.

Between the point where the trigger arm 36 is pivoted to the brackets 34 and 35 and the end of the arm to which the loop 39 is located, a lifter arm 44, is pivotally secured to a block 46, which is secured to the vertically disposed plunger lifting rod 47.

Extending backwards from the block 46 is a plate 48 which may if desired be integral with the block 46 from which extend the horizontally disposed plunger lifting pins 49, which pass through the series of plungers 50.

The plungers 50 are disposed in a tank 51 and the lower ends thereof act as valves for the openings 52 provided in the bottom of the tank. Supported from the walls of the tank 51 is a guide cage 53 having aligned

openings in which the rod 47 and the plungers 50 are adapted to reciprocate.

An extension of the tank 51 extends over a fire box 54 whereby the tar, oil or other substance used in repairing, may be heated so that it will have the proper consistency to flow easily or be sprayed by air pressure.

The embodiment shown in the present application shows a battery of eight plungers, 10 but it is self-evident that the number of the plungers may be varied and also that a duplicate battery having its own trigger arm may be disposed in alignment with that shown in this embodiment.

15 Secured to the two central plungers of the back set of four plungers are the arms 55, which terminate in a horizontally disposed portion 56 having an aperture 57 therein.

20 Immediately in back of the plunger battery are two bins 58 and 59. The bin 58 is adapted to contain small aggregate and the bin 59 contains a larger size aggregate. The openings of the bins 58 and 59 are placed one above the other as shown in Figure 1 and the bin 58 is closed by the sliding door 60 having rod 61 attached thereto, which passes through the aperture 57 in the member 56 and terminates with an enlarged head 62. The door 63 of the bin 59 terminates in a right angular portion 64 having an aperture 65 therein through which the rod 61 also passes.

25 Disposed above the tank 51 is a reservoir 66 which may if desired be carried on a truck or trailer for the tank 51 and the reservoir has a pipe 67 leading to said tank and a valve 68 normally open in the pipe to control the flow of material to the tank 51. 30 The reservoir 66 is placed far enough above the plungers 50 so as to allow the proper reciprocation thereof.

35 If desired reservoirs for the bins 58 and 59 may also be placed upon my device or 40 may be carried by a trailer.

The doors 60 and 61 are inclosed in a U-shaped guard 69.

45 The weights 43 are adapted to reciprocate in tubular members 70 which are fastened to the brace bar 30 or on any other suitable part of the machine and serve as guides for the weights.

50 A hook 71 is secured to the brace bar 33 and is adapted to hook over the bar 36 when it is desired to hold the parts in inoperative position.

55 The operation of my device is as follows. The entire central machine is adjusted upon the staggered blocks 14 and 15 so as to properly adjust the roller 37 with relation to the road. Upon the roller 37 striking a depression the weights 43 will cause the roller 37 to descend into the depression and the bar 44 will move the plunger lifting rod 47 and with it the plungers 50 upwards.

This will uncover the openings 52 and tar will be deposited in the depression. Upon the upward movement of the plungers 50 the arms 55 will raise the rod 61 carrying with it the door 60 of the bin 58 and small aggregate will be deposited upon the tar. In case a deep depression is encountered the upper portion 72 of the door 60 will encounter the over hanging portion 64 of the door 63 and large aggregate will also be deposited. Upon the roller 37 ascending out of the depression the bar 44 will move the plungers 50 downward and close the openings 52 thereby shutting off the flow of tar. At the same time the bars 55 move downward and the doors 60 and 63 close by gravity. If desired nuts may be placed upon the bar 61 in order to compel the closing of the doors 60 and 63.

85 Whenever the supply of tar in the receptacle 66 is low the valve 68 may be closed and a new supply obtained for the reservoir 66.

90 The whole device is adapted to be drawn upon the skids by horses or any other means along the road that is to be repaired. It is evident that the skids 10 and 11 may be provided with wheels or rollers if desired.

95 Some changes may be made in the construction and arrangement of my invention above set forth without departing from the real purpose and spirit thereof, and it is my intention to cover by the following claims, any modified forms of structure or use of 100 mechanical equivalents, which may be reasonably included within their scope.

I claim:

1. In a device of the class described, a receptacle for road repairing material and means actuated by depressions in a road for 105 distributing said material upon said road.

2. In a device of the class described, a receptacle for aggregate a tank for tar or pitch and means actuated by depressions in a road for distributing said aggregate 110 and tar upon said road.

3. In a device of the class described, a receptacle for aggregate, a door therefor and means controlled by depressions in a road for raising said door.

4. In a device of the class described, a receptacle, a door for said receptacle, a tank for tar having openings in the bottom thereof plungers covering said openings and means actuated by depressions in a road for 120 raising said door and uncovering said openings.

5. In a device of the class described, receptacles for road repairing material, means actuated by depression in a road for distributing said material upon said road and means regulating the rate of flow of said material.

6. In a device of the class described, a bin for small aggregate, a bin for large aggre-

- gate, a tank for tar, means controlling the out flow from said bins and tank and means regulating said controlling means actuated by irregularities in a road.
5. 7. In a device of the class described, a vehicle adapted to be drawn along a road, a receptacle for road repairing materials carried by said vehicle having an outlet and means actuated by irregularities in the 10 surface over which the vehicle is drawn controlling said outlet.
8. In a device of the class described, a vehicle, a receptacle carried by said vehicle having an outlet and a trip rod in contact 15 with the surface over which said vehicle is drawn and means connected to said trip rod controlling said outlet.
9. In a device of the class described, a vehicle, a receptacle carried by said vehicle having an outlet, means whereby the distance 20 of the receptacle from the surface of the road may be varied and means contacting the ground controlling said outlet.
10. In a device of the class described, a 25 vehicle, receptacles carried by said vehicle having outlets, valves controlling said outlets means actuating said valves and means maintaining said actuating means in constant contact with the surface over which the vehicle is moved.
11. In a device of the class described, a bin for small aggregate having a door, a bin for large aggregate also having a door and means whereby the second mentioned 35 door is opened when the first mentioned door has entirely uncovered the outlet in the small aggregate bin.
12. In a device of the class described, a 40 vehicle, a receptacle carried by said vehicle and maintained in adjustable relation thereto, said receptacle having an outlet closed by a sliding door, a tank having openings in the bottom thereof plungers closing said openings, a trip rod pivotally carried by said 45 tank, a roller at one end of said trip rod weights secured to the other end of said trip rod maintaining said roller in constant contact with the road surface and means connected to said trip rod for raising said door and plungers.
13. In a device of the class described, a receptacle containing road repairing material, and means actuated by irregularities in the road for depositing said material in 50 said irregularities.
14. A road repairing device comprising a vehicle adapted to be drawn along a road, a receptacle carried by said vehicle having an outlet, means closing said outlet, a tank having openings in the bottom thereof, 60 means closing said openings and means in contact with the road adapted to open said outlet in said receptacle and said openings in said tank.
15. A road repairer comprising a bin having an outlet and means actuated by the 65 depth of the depressions in the road and in proportion thereto for controlling the size of said outlet.
16. A road repairer comprising a series 70 of bins having outlets and means governed by the road contour for successively uncovering said outlets.
17. A device of the class described, comprising a series of bins adapted to contain 75 road repairing materials and means operated automatically by the road contour for spreading said materials upon a road.
18. A road repairer comprising a series of receptacles, said receptacles having outlets, 80 means governed by the road contour for uncovering the outlet of one of said receptacles and means governed by said first mentioned means for uncovering the outlets of the other receptacles.
19. A road repairer comprising a series of 85 receptacles, said receptacles having outlets, means governed by the road contour for uncovering the outlet of one of said receptacles and means governed by said first mentioned means for successively uncovering the outlets of the other receptacle.
